UNITED STATES PATENT OFFICE

ROWLAND W. RIDER, OF SALT LAKE CITY, UTAH, ASSIGNOR TO UTAH ROYALTY CORPORATION, OF SALT LAKE CITY, UTAH

AUTOMOBILE DOOR LATCH AND OPENER

Application filed November 23, 1929. Serial No. 409,408.

My invention relates to door opening devices and has for its object to provide means in combination with the usual door latch by which on withdrawal of the latch from engagement with the usual strike plate the door will be swung sufficiently to start it open.

The door latch in ordinary use comprises a sliding latch member with beveled end pressed into locking position by a spring and a knob or handle for withdrawing it from locking position by a twist of the knob or handle. With doors which fit snugly such as the doors of automobiles the twisting of the handle which withdraws the latch has to be supplemented by a substantial pull on the handle to start the door from closed position. It is an object of my invention to provide means for obviating the necessity for the pull on the door handle by providing means by which the twisting of the handle to withdraw the latch will act to start the door away from the door jamb. A further object of my invention is to provide means for effecting the initial opening movement which will be simple, inexpensive and efficient.

With the objects above indicated and other objects hereinafter explained in view my invention consists in the construction of elements hereinafter described and claimed.

Referring to the drawings:

Figure 1 is a side view of a door latch embodying my invention, the casing being partly broken away.

Figure 2 is a top plan view of the latch shown in Figure 1 without the casing showing the latch in locking position, and

Figure 3 is a view similar to Figure 2 but showing the latch in withdrawn position.

In the drawings 1 indicates the sliding member or plunger of a door latch of usual construction pressed forward to engage the strike plate on the door jamb by a spring 2 and withdrawn from engagement by the usual cam 3 on the shaft 4 of the usual door handle 5, this cam being adapted to act, when the handle is turned, against a downwardly extending projection 6 carried by the sliding member or latch bolt 1, to withdraw it from engagement with the strike plate and permit the door to be swung open. The construction

so far described is conventional and is illustrative of one of the forms of door latch to which my invention may be applied.

In my invention the sliding member or plunger 1 is provided with a cam guide way 55 7 extending through it, preferably at its upper edge, to receive the curved portion 8 of a push member 9 pivotally connected at its rear end to the latch casing and having its forward or free end 10 adapted to engage 60 the side of the opening in the strike plate or other fixed portion of the door jamb. This push member is here shown as carried by a pin or screw 11 extending through a slot 12 in the rear end of the push member into the 65 plate 13 of the latch casing. This slot is of such length relative to the screw or pin 11 as to permit the push member to swing on an axis at right angles to the line of movement of the latch bolt being yieldingly held 70 against such movement by a spring 14 between the head 15 of pin or screw 11 and the push member, the spring bearing at one end against the head 15 and at the other end bearing against the end portion of the push 75 member so that it will tend to hold the end of the push member against the plate 13 as shown in Figure 2 but will yield to permit the push member to assume the position in which it is shown in Figure 3. Any other piv- 80 otal means may be used for connecting the push member with a fixed portion of the latch casing.

In closing the door the bevelled end 16 of the sliding member or plunger 1 as it strikes the usual strike plate on the door jamb will be forced back against the force of spring 85 2. As it is thus forced back the cam guide way 6 will act upon the curved portion 8 of the push member 9 to force its end 10 towards the door jamb. The end of the sliding member or plunger comes in line with the opening in the strike plate and is forced forward by spring 2 into latching engagement with the 90 striker plate.

In this latching movement the push member by reason of the engagement of its curved portion 8 with the cam guideway 6 presents no obstacle to the latching movement and in 100

fact may assist the action of spring 2 as the free end 10 strikes the strike plate.

When the door is to be opened the handle 5 is turned as usual to force cam 3 against projection 6 on the sliding member or plunger 1 to forcibly withdraw it from its latching engagement with the strike plate. As the sliding member or plunger 1 is thus withdrawn its cam way 7 acting on curved portion of the push member causes its free end 10 to press against the door jamb and so to force the door away, thus starting the opening swing of the door on its hinges.

While the device thus described is particularly adapted and intended for use on automobile doors it may be used on latches for any swinging doors, and while adapted for use with sliding bolts is independent of particular means for moving the sliding bolt in either direction.

Having thus described my invention, what I claim is:

1. In a door latch, a sliding latch bolt and means for moving it into and out of latching position, means operated by the latch bolt for acting against the door jamb to start the door towards open position comprising a cam carried by the latch bolt and a push member mounted to swing horizontally on a fixed pivot and having its free end in position to be acted on by the cam of the latch bolt.
2. In a door latch, a sliding latch bolt having a recess in one edge, means for moving the latch bolt into and out of latching position and means operated by the latch bolt for acting against the door jamb to start the door toward open position comprising a push member arranged in said recess of the latch bolt having its rear end held against movement longitudinally of the latch bolt and having its free end adapted to be projected into contact with the door jamb.
3. In a door latch, a sliding latch bolt having a recess in one edge, means for moving the latch bolt into and out of latching position and means operated by the latch bolt for acting against the door jamb to start the door toward open position comprising a push member arranged in said recess of the latch bolt having its rear end held against movement longitudinally of the latch bolt and having its free end adapted to be projected into contact with the door jamb and means carried by the latch bolt for acting upon the free end of the push member to project it against the door jamb.

In testimony whereof, I hereunto affix my signature.

60 ROWLAND W. RIDER.
